UNITED STATES PATENT OFFICE

RICHARD R. MEAD, OF QUEENS VILLAGE, NEW YORK, ASSIGNOR TO MERGENTHALER LINOTYPE COMPANY, A CORPORATION OF NEW YORK

TYPOGRAPHICAL COMPOSING MACHINE

Application filed March 26, 1930. Serial No. 438,945.

This invention relates to typographical composing machines, such as linotype machines of the general organization represented in U. S. Letters Patent No. 436,532, wherein circulating matrices are released by escapements from a channeled magazine in the order in which their characters are to appear in print, the composed line transferred to the face of a mold, the mold filled with molten metal to form a slug or linotype against the matrices which produce the type characters thereon, and the matrices thereafter returned through distributing mechanism to the magazine from which they started. In these machines, as the matrices are released from the magazine, they pass into a so-called assembler entrance, provided with a series of vertically disposed guides or partition plates, which guide and direct the matrices onto a constantly-driven assembler belt discharging into the assembler.

The matrix guides ordinarily comprise each an upper rigid section which is fastened in the upper end of the assembler entrance, and a lower resilient or flexible section attached to and depending from the upper section, the resilience of the lower section being necessary to enable the matrices to be deflected from their substantially vertical paths of travel onto the horizontal or inclined portions of the assembler belt. It should be noted at this point that the resilient sections of the partitions are subjected to repeated and frequently recurring flexings and bendings in the passage of the successive matrices through the assembler entrance in the composing operation, which flexings are more pronounced where, as in an auxiliary assembler entrance, the matrices are deflected from a truly vertical path onto a horizontal portion of the assembler belt; and the flexings and bendings of the lower resilient sections are also quite pronounced where unusually thick or display matrices are handled.

In the construction of these matrix guides or partition plates as heretofore practiced, different methods of attachment of the lower or resilient section to the upper rigid section have been resorted to, but without proving entirely satisfactory. For instance, it has

been the practice to attach the lower section to the upper section by means of spot-welding, but in use the resilient section, owing to the frequent flexing and bending actions referred to, often breaks from the upper section at the edge of the latter, which breakage it is believed is caused by the crystallization of the metal due to the application of heat in the welding operation.

The present invention aims to provide a matrix guide or partition plate which will not be open to this and other objections, and the invention consists in a guide or partition of improved form and construction, characterized by the connection of the lower resilient section to the upper rigid section in such manner that there will be little or no danger of breakage or displacement of the parts. In the specification to follow, the invention will be described in detail and the novel features thereof will be set forth in the appended claims.

In the accompanying drawings:

Fig. 1 is a front elevation of a portion of a linotype machine, equipped with both a main assembler entrance for the main magazine, and an auxiliary assembler entrance for an auxiliary magazine, the front plates of said entrances being broken away to show the matrix guides or partition plates therein. Fig. 2 is a perspective view of the sections of one of the improved matrix guides, disconnected from each other;

Fig. 3 is a perspective view of said sections assembled in operative relation preparatory to being connected together in accordance with the invention;

Fig. 4 is a similar view showing the sections connected together and forming the complete improved matrix guide;

Fig. 5 is a view in cross section, showing the successive stages in effecting the connection of the two sections;

Fig. 6 is a fragmentary perspective view on an enlarged scale showing the local deformation of the overhanging edge of the recess in the rigid section, to interlock with the cavity in the resilient section;

Fig. 7 is a similar view showing the overhanging edge of the rigid section deformed

or bent down into firm engagement with the upper end of the resilient section.

Referring to the drawings:

As shown in Fig. 1, the matrices from a main magazine 1 are, by means of finger keys 2, released from the magazine and pass through a main assembler entrance 3 onto the inclined portion of an assembler belt 4, by which they are delivered to the assembler elevator 5; and in the machine illustrated, an auxiliary magazine 6 is employed, the matrices of which pass through an auxiliary assembler entrance 6^a onto a horizontal extension 7 of said assembler belt, whereby said matrices along with those from the main magazine, are delivered to the assembler elevator.

These assembler entrances comprise back plates 8 and 9 and front plates 10 and 11 respectively, and are divided into channels as usual by upright matrix guides or partition plates 12, comprising each an upper fixed section fastened to the upper end of the back plate, and a lower resilient section connected at its upper end to said upper section so as to depend therefrom between said front and back plates, all as shown in Fig. 1.

It is with these matrix guides or partition plates 12, and the method of connection of the two sections thereof, that the present invention is particularly concerned, the novel manner of effecting such connection in accordance with the invention and without the application of heat, providing a construction in which the lower resilient section, subject to repeated and oft recurring flexings and bendings incident to the assembling of the matrices into line, will be supported at its upper end without danger of breakage or displacement, and the crystallization of the metal heretofore the cause of their frequent breakage, will be avoided.

The detailed form of the improved matrix guide and method of constructing the same are shown in Figs. 2 to 7, where it will be seen that the upper rigid member or section 13 of the matrix guide, formed as usual with the two rearwardly extending fingers 13^a, for attachment to the back plate of the assembler entrance in the customary manner, is provided in its side face with an undercut recess 15, presenting an overhanging marginal edge or wall 16. This recess is of general semi-circular contour to receive the upper rounded end 14^a of the lower resilient member or section 14, as shown in Fig. 3, the opposite edges of which are formed with cuts or notches 17.

In the assemblage and connection of the parts thus formed, the rounded upper end of the resilient section is first seated in the recess 15, as shown in Fig. 3, and when so seated, the marginal edge or wall 16 of the recess will overhang the edge of the rounded end 14^a and the two cuts or notches 17, as best

shown in view A, Fig. 5. By suitable means, the overhanging edge 16 of the recess is forcibly bent down against the side of the rounded end of the resilient section so as to bind tightly and firmly against the same, as shown in view D, Fig. 5, whereby said end of the section will be held frictionally against endwise displacement or escape from the recess, and whereby it will also be held positively against lateral displacement, so that in this way an effective and durable connection of the two sections is obtained which is not liable to breakage or displacement under the frequent bendings to which the section is in practice subjected.

As a further means of preventing the endwise escape of the resilient member from said recess, the inwardly bent wall of the recess is deformed locally into interlocking engagement with the end of the resilient section, which is effected by staking or driving into the cuts or notches 17, the portions of the wall 16 overlying said notches, as shown at 18 in views B and C of Fig. 5, and in Figs. 4 and 7. Or these local deformations of the overhanging wall may be effected before the wall is bent down, as shown in Fig. 6. In either case, the effect is to bring about an interlocking of the two sections of such character as to positively prevent the endwise displacement or escape of the resilient section from the recess in the rigid section.

By fastening the upper end of the resilient lower section of the matrix guide in a recess in the side of the upper rigid section thereof, the side face of said end will not project beyond the side face of the rigid section and thereby offer obstruction to the passage of the matrices downwardly through the channels constituted by said guides. The matrix guides or partitions constructed as above described, will therefore present effective and smooth guiding surfaces for the down-traveling matrices as they pass through the assembler entrance, while at the same time the resilient portions of said guides are free to bend and flex laterally as the matrices are deflected onto the assembler belt, and this without danger of breakage from continued bending.

To give the matrix guide a finished appearance and to fill in and cover over any fine spaces or crevices that may be left after the deformation of the metal in fastening the sections together as above described, the completed guide as shown in Fig. 4, may have a plating of a suitable metal, such as nickel, applied thereto, as shown at 19 in Fig. 7.

While I have illustrated and described the improved matrix guide or partition as being employed in the assembler entrance of a linotype machine, the invention in its broader aspects is not limited to such use, but is applicable also in other locations in a linotype machine and wherever it is necessary to subject the matrices to a guiding action while

at the same time permitting of a deflection of the matrices from their path of travel.

Having thus described my invention, what I claim is:—

- 5 1. The improved matrix guide plate or partition for linotype machines, comprising a rigid section, and a resilient section connected thereto by frictional engagement of its upper end with said rigid section.
- 10 2. The improved matrix guide plate or partition for linotype machines, comprising a rigid section, and a resilient section having an interlocking connection at its upper end with said rigid section.
- 15 3. The improved assembler entrance guide or partition, comprising an upper rigid section and a lower resilient section having its upper end connected with the rigid section by frictional engagement therewith.
- 20 4. The improved assembler entrance guide plate or partition, comprising an upper rigid section and a lower resilient section having an interlocking connection at its upper end with said rigid section.
- 25 5. The improved assembler entrance guide or partition comprising an upper rigid section and a lower resilient section connected to the upper section by both a frictional and an interlocking engagement therewith.
- 30 6. The improved assembler entrance guide plate or partition, comprising an upper rigid section having a recess in its side face, and a lower resilient section having its upper end seated and secured in said recess.
- 35 7. The improved assembler entrance guide or partition, comprising an upper rigid section provided in its side with an undercut recess, and a lower resilient section having its upper end seated and secured in said under-
40 cut recess.
8. The improved assembler entrance guide or partition, comprising an upper rigid section provided in its side with an undercut recess, and a lower resilient section having its upper end seated in said undercut recess, the marginal edge of the recess being deformed so as to bear tightly against and confine said upper end of the resilient section.
- 45 9. The improved assembler entrance guide or partition, comprising an upper rigid section provided with a recess presenting an overhanging marginal edge, and a lower resilient section seated at its upper end in said recess and provided in its edge with a
50 notch, said overhanging edge of the recess being deformed locally and seated in the said notch to prevent endwise displacement of the lower section.
- 55 10. The improved assemblage entrance guide or partition, comprising an upper rigid section provided with a recess presenting an overhanging marginal edge, and a lower resilient section having its upper end provided with a notch and seated in said recess,
60 65 the marginal edge of the recess being de-
- formed so as to bear tightly against and confine the upper end of the resilient section against lateral displacement, and said marginal edge being further deformed locally and seated in the said notch to confine the resilient section having its upper end pro-
